UNITED STATES PATENT OFFICE.

CHARLES R. EDWARDS, OF PEKIN, ILLINOIS.

PUMP.

1,084,413.

Specification of Letters Patent. Patented Jan. 13, 1914.

Application filed April 2, 1913. Serial No. 758,378.

To all whom it may concern:

Be it known that I, CHARLES R. EDWARDS, a citizen of the United States, residing at Pekin, in county of Tazewell and State of Illinois, have invented certain new and useful Improvements in Pumps, of which the following is a specification.

My invention relates to an improvement in pumps, and more particularly to such devices of the double-acting or force-pump type in which a constant stream flows at the outlet.

The object of this invention is to produce a pump which may be used in elevating water or other liquids, and which is simple and efficient in its operation.

This invention relates to still other novel features of construction and combinations of parts which will be hereinafter described and set forth in the claims.

In the accompanying drawings: Figure 1 is a view in vertical section to show the arrangement and assembling of the parts; Fig. 2 is an enlarged transverse sectional view on the line 2—2 of Fig. 1; Fig. 3 is a view in top plan of the piston rod guide; and Fig. 4 is a detail bottom plan view to better illustrate the form of one of the valves.

The cylinder A has the piston B mounted to reciprocate therein, and this piston has the packing washers 1 and 2 so connected therewith that a liquid-tight connection is formed between the piston and the inner wall of the cylinder on both the up and down strokes. The piston rod 3 is secured to the piston, and extends up through the cylinder and through a guide 4 held positioned in the cylinder near the upper end thereof. Near the bottom of the cylinder A a plug 5 is held by being screwed into the cylinder or in any other approved manner. This plug is open at its center at 6, and a valve 7 is received in the opening to permit the passage of liquid up through the opening and to close the opening to the passage of liquid in a downward direction.

A branch pipe C is formed integral with the cylinder A, and an opening 8 establishes communication between the cylinder A to a point above the guide 4, where communication is again established with the interior of the cylinder through an opening 9. A plug 10 is screwed or otherwise held in the branch C above the opening 8, and this plug has a central opening 11. A valve 12 is

mounted in the opening to permit the passage of liquid from the opening 8 to the body of the branch C, and to close the opening to the back flow of liquid in a downward direction. A plug 13 closes the branch C at the lower end, and communication with the passage is thus limited to the opening 8 from the cylinder and the opening 9 into the cylinder.

A flap valve 14 is held in an opening 15 formed through the wall of the cylinder at a point below the guide 4, and, as better shown in Fig. 2, this flap valve is constructed to swing in, and thus liquid can pass into the cylinder A through the opening 15, but the passage from the cylinder through this opening is precluded by the valve 14.

The guide 4 has a central opening 16 through which the piston rod 3 has sliding movement, and slot openings 17, 17 are provided through the guide around the opening 16. A valve washer 18 is received around the shank 19 of the guide 4, and is adapted to fit normally over and close the slotted openings 17. A valve 18 is held in its closed position by a coiled spring 20, which is received around the shank 19 and is held by pins 21.

It is the intention that the structure as described be submerged in the liquid to be elevated, but if desired, a pipe 22 may be carried from the lower end of the cylinder A to the liquid and a similar pipe can be fitted to supply the liquid to the opening 15. In this way, the pump structure can be set at any point.

The flow of the liquid pumped is through the opening 23, and it is evident that the liquid might be carried to any distance by a pipe which can be screwed in the screw threads 24.

The operation of the pump is as follows: The piston is moved on its upward stroke to the position shown in Fig. 1. The liquid is drawn up through the opening 6, and fills the cylinder below the piston. The piston is then moved in a downward direction, and the liquid is forced up through the opening 11 in the plug 10, but is held in the branch C. At the same time liquid is drawn into the cylinder above the piston through the opening 15. The piston is again moved in the upward path and the liquid in the upper part of the cylinder is expelled through the slotted openings 17. This operation is continued, and the liquid in the

body of the branch C and in the cylinder A above the guide 4 is forced out through the opening 23 in a constant stream.

It is evident that slight changes might be made in the form and arrangement of the several parts without departing from the spirit and scope of my invention, and hence I do not wish to limit myself to the exact description herein set forth, but—

10 Having fully described my invention, what I claim as new and desire to secure by Letters Patent is:

1. A pump comprising a cylinder, a piston mounted to be reciprocated in said cylinder, a piston rod connected to and for reciprocating said piston, a guide located in the upper part of the cylinder through which said piston rod has endwise movement, an intake valve located in the lower part of the cylinder, a branch formed from the cylinder and connecting therewith at its lower end at a point above said valve and at its upper end at a point above the guide, an intake valve located in the branch 25 above the opening from the cylinder, an intake valve located in the upper part of the cylinder below the guide, said guide provided with openings through which the liquid passes from the lower to the upper side, and a valve received around the guide to normally fit over and close said opening.

2. A pump comprising a cylinder, a double-acting piston received in the cylinder, a piston rod connected with said piston

to transmit reciprocatory movement thereto, 35 a guide secured in the bore of the cylinder near the upper end through which the piston rod has sliding movement, a plug having an opening therethrough secured in the bore of the cylinder near the lower end, a valve 40 located in the opening to permit the passage of liquid upwardly therethrough and to close the passage to liquid moving in a downward direction, a branch connecting with the cylinder at its lower end above the 45 plug and at its upper end above the guide, a plug provided with a passage therethrough secured in the branch above the opening from the cylinder, a valve located in the passage to permit the passage of liquid in an 50 upward direction and to close the passage to the back flow of the liquid, an inlet valve located in the upper part of the cylinder below the guide, said guide provided with openings through which the liquid may 55 pass, a valve received around the guide to fit over said openings, and resilient means for holding the valve normally in a position that the liquid can pass in an upward direction, but is prevented from flowing in a 60 downward direction.

In testimony whereof I affix my signature, in the presence of two witnesses.

CHARLES R. EDWARDS.
